WILLIAM LINN CULBERTSON, OF THE UNITED STATES NAVY, WORLAND, WYOMING

METHOD AND APPARATUS FOR RAISING SUBMERGED SHIPS

Application filed January 26, 1927. Serial No. 163,626.

My invention is designed to provide an improved method of and apparatus for raising vessels which through accident or mischance have been sunk and are partly or completely submerged in water, and it contemplates displacing the water inside the vessel and raising or increasing the buoyancy of the submerged hull by the delivery thereto from a suitable source of supply of rigid buoyant devices, such as sealed, hollow, metallic balls, which are impermeable to water and have high resistance to crushing. The resistance of the balls to crushing is largely due to making them of spherical form and may be increased by placing the balls under an initial internal pressure. The buoyant devices are preferably introduced into the vessel by the weight of an accumulation of such devices above level of water in a conduit through which the balls are supplied. The weight of such devices forces the lower buoyant devices downward through the water in the lower part of the supply conduit and into the interior of the hull with which the lower portion of the conduit communicates. The distance the balls must be moved through water before escaping from the conduit into the hull, and consequently the accumulation and weight of the balls necessary to effect such movement through the water, may be regulated by forcing down the water level in the conduit below the level of the water submerging the vessel. This may be effected by introducing into the conduit a fluid under pressure of lower specific gravity than the balls themselves; such compressed fluid permitting the balls to fall freely therethrough but forcing back the water level toward or to the lower end of the conduit. By my improved method and apparatus, it is possible to utilize the force of gravity acting on the ball or the like passing through a fluid having a specific gravity lower than the ball for carrying it the greater part of the distance necessary for delivery to the hull, and to then utilize the weight of, or the force of gravity acting on, an accumulation of such buoyant devices for forcing the lower devices into the hull in sequence through water of higher specific gravity than any individual device.

In the preferred practice of my invention, a flexible tube or conduit is so connected with a submerged hull as to communicate with the interior thereof and the bulk of the water is forced out of the conduit by means of compressed air, compressed gases, steam or the like, preferably leaving a water seal adjacent to the lower portion of the conduit. Hollow, metallic balls are then inserted in the conduit until the weight of balls accumulated in the space above the water level is sufficient to force balls lying in or upon the water at the bottom of the conduit through the water seal and into the hull. Preferably the depth of water in a conduit is so proportioned to the length of the conduit that balls pile up to near the inlet to the conduit before their weight is sufficient to force the lowermost ball out of the bottom of the conduit. Consequently the balls fed into the conduit inlet have but a short fall: or if a shallow water seal is used the descent of the ball through the water-free space may be checked at suitable intervals, if desired, by friction devices carried by the conduit to prevent injury to the balls by impact.

The balls are preferably delivered to the conduit from a plurality of chambers which alternately are placed in communication with the conduit and closed to the atmosphere and then cut off from the conduit and opened to the atmosphere; the balls being inserted in the chamber while the conduit is cut off therefrom and discharged into the conduit while the chamber is cut off from the atmosphere to avoid excessive loss of the compressed fluid.

It will, however, be understood that where a vessel is sunk in such shallow water that the normal depth of water in the supply conduit is not great, the balls may be forced through such water in the submerged portion of the conduit and into the hull without any necessity for lowering the level of the water in the conduit. This may be done by filling a conduit section with a proper number of balls and elevating the end of the filled conduit, or by attaching the inlet end of the conduit to a mast or other elevated structure and ac-

cumulating a sufficient number of the balls therein to force the lower ones out.

The characteristic features and advantages of my improvements will more fully appear from the following description and the accompanying drawings in illustration thereof.

In the drawings, Fig. 1 illustrates diagrammatically the salvaging of a sunken vessel by means of my improvements; Fig. 2 is a similar view taken at right angles to the view shown in Fig. 1; Fig. 3 is a diagrammatic view illustrating a preferred form of mechanism for expelling water from and supplying buoyant devices to a conduit leading to the submerged ship; Fig. 4 is a side elevation of a reservoir or magazine from which the buoyant devices are supplied to the conduit; Fig. 5 is a sectional view of one of the buoyant devices; and Fig. 6 is a fragmentary sectional view illustrating the application of a descent checking device to a portion of a conduit by which the buoyant devices may be delivered to the submerged ship.

In accordance with my invention, the submerged ship which it is desired to raise to the surface of the water is first emptied of cargo as far as possible so as to provide the largest possible space within the hull for buoyant devices, which are preferably rigid, spherical, hollow steel balls, and may be of any desired size. Preferably, however, the balls are made from twelve to sixteen inches in diameter.

The hatchways and other large openings in the hull are preferably closed by means of gratings or bars preventing the escape of balls but permitting the escape of water from the hull.

The buoyant devices or hollow balls 1 are transported to the vicinity of the submerged vessel "A" by a salvaging vessel B and are delivered from the salvaging vessel into the interior of the submerged vessel by means of strong flexible conduits or hoses 2 having their lower or discharge ends 3 communicating with various portions of the interior of the hull A through ports already existing or through apertures cut in the hull by divers for the purpose. The conduits or tubes may be so positioned that the balls discharged therefrom will reach all empty parts of the hull and may be fixed to the hull in any desired manner.

The buoyant devices may be forced through the conduits into the submerged hull by the direct action of fluid pressure thereon, but as this necessitates overcoming the buoyancy of the balls for the whole length of the submerged portions of the conduits, I prefer to utilize the weight of unsubmerged balls to force floating or submerged balls through the water in or at the outlet from the submerged portion of the conduits. To minimize the weight required for this, it is desirable to expel the water from the greater portions or

all of the submerged lengths of the conduits by the pressure of a fluid such as air, gas or steam having a specific gravity lower than the specific gravity of the balls or buoyant devices, which consequently fall by gravity through the tube down to the water level indicated at 4 in the lower portions of the tubes. It is, of course, possible to completely expel the water from the conduit or tube, but this may involve an excessive loss of compressed fluid, and this loss is minimized by permitting a water seal to remain in the lower portion of the tube. The depth of this water seal is preferably such that the tube is nearly filled with balls before the lowermost ball is forced out, and additional balls then entered at the top of the tube or conduit force the same number of balls out of the bottom of the conduit and into the hull. Should the depth of the water seal be shallow proportionately to the length of the tubes, the descent of the balls or buoyant devices through the water free section of the tube or conduit may be checked, so as to avoid injury by impact of the balls with one another, by a frictional ring 6 of leather, rubber or the like clamped between the flanges of a coupling 7 connecting sections of the conduit or tube 2 together. The aperture or opening in the ring 6 is such as to prevent free passage of the balls therethrough and check, without stopping, their downward descent.

The upper ends of the respective conduits 2 may be provided with gate valves 8, and when in use for supplying buoyant devices to the submerged hull are respectively connected with a delivery tube 9 of mechanism for supplying a substantially continuous stream of balls to the tube. This mechanism preferably comprises a plurality of chambers 10 and 11 communicating through the throat 12 with a tube section 9: communication between the respective chambers 10 and 11 and the throat 12 being controlled by a valve 13 movable on the pivot 14 by an arm 15 operable by the link 15'. The opposite ends of the chambers 10 and 11 are provided with ports which may be tightly sealed by gates or valves 16 secured in place by the fasteners 17. These fasteners may be controlled by pistons or plungers 18 movable in cylinders 19 communicating with the interiors of the respective chambers 10 and 11, and may be supplemented by fasteners 17'.

Fluid under compression, such as air, may be supplied from a pump 21 to an accumulator 22 which is connected by the conduit 23 and the automatic pressure control valve 24 with the throat 12 so that the pressure in the throat 12 and in the conduit sections 9 and 2 may be maintained substantially constant.

The accumulator may be connected with the chamber 10 through a conduit 25 and valve 26. The valve 26 also has parts by which the chamber 10 may be connected with the at-

mosphere when not connected with the accumulator. The accumulator 22 may be connected with the chamber 11 through the pipe 27 and valve 28, the latter having parts for connecting the chamber with the atmosphere when not in communication with the accumulator.

A movable tray 33 may be used for delivering balls of buoyant devices 1 to the several chambers 10 and 11 when the respective doors 16 are opened.

In the preferred practice of my invention, the end of a tube 2 is connected with the submerged hull and its upper end is connected with a section 9. The chambers 10 and 11 are filled with balls from the tray 33 and the doors 16 are locked in closed positions. Air under pressure is admitted to the throat 12 and forces the water out of a desired portion 20 of the length of the conduit 2. The balls from the chamber 10 are permitted to pass through the throat 12, conduit 9, past the valve 8 and into the tube 2. The accumulated weight of the column of balls in the tube 25 2 forces the lowermost balls out the lower end of the tube and into the hull of the submerged vessel. When all of the balls have been discharged from the chamber 10, the valve 13 is turned so as to close this chamber and permit 30 the balls from the chamber 11 to pass through the throat 12, tube 9, past the valve 8 and into the tube 2. Meanwhile the valve 26 has been so turned as to permit the escape of compressed air from the chamber 10, and when 35 the pressure in such chamber has been sufficiently reduced, the fastener 17 may be operated and the gate 16 opened. A new charge of balls is then delivered to the chamber 10 from the tray 33, the gate 16 is closed, and pressure is admitted to the chamber 10 by 40 turning the valve 26. Any high pressure in the chamber presses the piston 18 outward and prevents the inadvertent opening of the gate 16. When all of the balls have been discharged from the chamber 11, the valve 13 is again swung so as to close this chamber and permit the passage of balls from the chamber 45 10 into the tube 2. Meanwhile the pressure in the chamber 11 is released through the valve 28, a new charge of balls is admitted to the chamber, and the pressure in the chamber 11 is again raised by compressed air admitted 50 through the valve 28.

The chambers 10 and 11 are thus used alternately to supply a substantially constant stream of balls through the tube 2 until the portion of the submerged hull which can be reached by balls delivered through the tube has been filled. Another tube 2, connected 55 with a different portion of the vessel, may be then connected with the tube 9 and the operation repeated until the hull has been filled with a sufficient number of balls to raise it or give it sufficient buoyancy for manipulation.

Under certain conditions, it may be desir-

able to inject into the hull a fluid or plastic buoyant material such as paraffine or a mixture of paraffine and cork to fill the interstices between the balls and distribute the pressure on the balls and hull members. The balls may 70 also be placed under an internal pressure, during manufacture, if desired.

Having described my invention, I claim:

1. The method of raising a submerged vessel which comprises utilizing the weight of 75 buoyant devices in one fluid for forcing similar devices through a heavier fluid beneath the surface of the body in which the vessel is submerged and into such vessel.

2. The method of raising a submerged vessel which comprises supplying thereto devices heavier than air and lighter than water by accumulating such devices in air above 80 other similar devices in water below the surface of the vessel submerging body so that the weight of the devices in air forces the devices 85 in water into the vessel.

3. The method of raising a submerged vessel which comprises delivering buoyant devices to the vessel through a conduit having 90 a submerged portion containing a fluid of lower specific gravity than the buoyant devices.

4. The method of raising a submerged vessel which comprises delivering buoyant devices thereto through a conduit having a submerged portion discharging to said vessel, said buoyant devices being superimposed upon one another in said conduit and the lower devices being forced from the submerged conduit portion into the vessel by 95 the weight of the superimposed devices.

5. The method of raising a submerged vessel which comprises delivering buoyant devices thereto through a conduit having a submerged section from which water is excluded by pressure of a fluid of lower specific gravity than the buoyant devices, said buoyant devices being superimposed upon one another in said conduit and the lower devices being 100 forced into the vessel by the weight of the superimposed devices.

6. The method of raising a submerged vessel which comprises delivering buoyant devices thereto through a compressed air filled 105 conduit down which said devices descend in sequence by gravity and checking the descent of the descending devices before they contact with previously fallen devices.

7. The method of raising a submerged vessel which comprises delivering thereto buoyant devices through a conduit containing fluid at a pressure higher than atmospheric, supplying fluid under pressure to a chamber containing a charge of buoyant devices and establishing communication between said chamber and conduit and delivering said charge from said chamber to said conduit. 115 120 125

8. The method of raising a submerged ves-

sel which comprises delivering buoyant devices thereto through a conduit and supplying said conduit with buoyant devices from a plurality of chambers in sequence.

5 9. The method of raising a submerged vessel which comprises delivering buoyant devices thereto through a conduit containing a fluid under pressure higher than atmospheric and connecting said conduit with a plurality of supply chambers in sequence, said chambers being alternately opened and sealed to the atmosphere.

10 10. The method of raising a submerged vessel which comprises delivering buoyant devices thereto through a conduit containing a fluid under pressure, maintaining a substantially constant pressure of fluid in said conduit, delivering buoyant devices to a supply chamber, supplying fluid under pressure 15 to said supply chamber, connecting said supply chamber and conduit, and delivering buoyant devices from said chamber to said conduit.

11 11. The apparatus for supplying rigid 20 buoyant devices to a submerged vessel which comprises a conduit, a supply reservoir for buoyant devices to be supplied to said conduit, means controlling communication between said reservoir and conduit, and means 25 for supplying fluid under pressure to said conduit and to said reservoir.

12 12. The apparatus for supplying buoyant 30 metallic devices to a submerged vessel which comprises a conduit, means for excluding water from a submerged portion of said conduit, and frictional means for checking the 35 passage of buoyant devices through said conduit.

13 13. The apparatus for supplying buoyant 40 devices to a submerged vessel which comprises a conduit, a plurality of chambers, valve mechanism connecting said conduit with said chambers in sequence, valve mechanism controlling the communication of said 45 chambers with the atmosphere, and means for supplying fluid under pressure to said conduit and to each of said chambers.

14 14. The apparatus for raising a submerged 45 vessel which comprises, a conduit, means for 50 supplying fluid under pressure to said conduit, means for supplying buoyant devices to said conduit, said devices being discharged from said conduit to said vessel, said means 55 for supplying said buoyant devices comprising a plurality of chambers, valve mechanism connecting said conduit with said chambers in sequence, said chambers having ports for the admission of buoyant devices thereto, and 60 means for sealing said ports.

15 15. The apparatus for supplying buoyant 65 devices to a submerged vessel which comprises a conduit, a chamber having a port controlled by a valve, means for supplying fluid pressure to said chamber, and means

70 preventing operation of said valve while said chamber contains fluid under high pressure.

In testimony whereof I have hereunto set my name this 22 day of January, 1927.
